AIR CONTROL RING

Ralph C. Brierly, Narberth, Pa.

Application July 6, 1948, Serial No. 37,178

4 Claims. (Cl. 158—1.5)

(Granted under Title 35, U. S. Code (1952),
sec. 266)

1

This invention relates to improvements in air-control registers of furnaces, and more particularly pertains to improvements in furnace air-control opening rings adapted for use as a burner throat or as a back plate in conjunction with air-control registers or diffusers. The subject device can be used either in conjunction with air-control registers such as those described in U. S. Patent to E. H. Peabody, No. 2,210,428, dated August 6, 1940, and in U. S. Patent to E. G. Peterson, No. 2,190,190, dated February 13, 1940, or with diffusers of the types disclosed in applicant's U. S. Patent applications No. 655,358, filed March 18, 1946, now abandoned; No. 724,219, filed January 24, 1947, now Patent No. 2,633,908, issued April 7, 1953; and No. 724,220, filed January 24, 1947, now Patent No. 2,638,974, issued May 19, 1953, singly or in groups, in lieu of conventional air-control registers.

The subject device provides structure of the general nature of strips or tabs in the form of curvilinear triangles filling the areas between the present-type circular or polygonal base rings of air-control registers and the adjacent curved bases of the register doors when the latter are in opened position. Such structure diminishes appreciably the tendency toward pulsation and unsteadiness of air flow and irregularity of combustion that are consequences of air slip along the lengths of the doors and from the lower edges of such doors.

The primary object of this invention is to provide air-register control structure adapted to control air flow about furnace fuel-injector elements, especially when the latter are grouped in clusters or rosettes.

Another object is to provide a furnace air-control opening ring adapted to minimize air slip along the lengths of register doors and from the lower edges of such doors, and to thereby diminish the tendency toward pulsation and unsteadiness of air flow and irregularity of combustion.

A further object is to provide an improved back-plate for air-control registers.

Other objects and many of the attendant advantages of this invention will be readily appreciated as the same becomes better understood by reference to the following detailed description when considered in connection with the accompanying drawings wherein:

Fig. 1 is a plan view of an air-control ring showing in phantom section a frusto-conical air-control door in operable position;

Fig. 2 is a section taken on the line 2—2 of Fig. 1;

2

Fig. 3 is a plan view of an air-control ring, showing another embodiment of the invention;

Fig. 4 is a section taken on the line 4—4 of Fig. 3;

Fig. 5 is a plan view of an air-control ring, showing still another embodiment of the invention, and showing in phantom diffuser-carrying hexagons in rosette form mounted therein;

Fig. 6 is a section taken on the line 6—6 of Fig. 5;

Fig. 7 is a plan view of an air-control ring constituting a further embodiment of the invention, showing in phantom a multiple arrangement of diffusers; and

Fig. 8 is a section taken on the line 8—8 of Fig. 7.

Similar numerals refer to similar parts throughout the several views.

20 The preferred embodiment of the invention shown in Fig. 1 comprises a ring 11 adapted to be mounted in the burner throat of a conventional furnace and a plurality of air-control surfaces 13. Said surfaces 13 together define

25 a frusto-conical member, and are so shaped as to each mate with the lower edge of one of a system of frusto-conical air control doors as such door is rotated about its hinged end. Such door 15 is shown in phantom section in Figs.

30 1 and 2, such door 15 being rotatable about a hinge positioned at point 17. Such door 15 is an element of a system of six frusto-conical air-control doors. In such structure, it is preferred to construct the air-control surfaces in such

35 manner that the radius of arc A equals the radius of arc B and the radius of arc C, with the radius of arc C being the radius of the lower edge of the frusto-conical air-control doors 15. Where a different number of doors is employed, other relative dimensions may prove optimum.

40 Each control surface 13 has the general shape of a spherical triangle, the base of the triangle being located on the ring 11 and the other two sides being directed toward the center of the ring 11. In lieu of the concave arrangement illustrated in Figs. 1 and 2, said surfaces can each be flat and can lie in the plane of the ring 11. In such form, said ring is of superior utility

45 when employed with multiple diffusers, especially when air registers such as the doors 15 are not used.

50 The modification shown in Figs. 3 and 4 includes a first ring 11 adapted to be mounted in the burner throat of a conventional furnace and a plurality of air-control surfaces 13 identical in shape and arrangement with those shown in

Figs. 1 and 2. Added thereto and carried in spaced relation therefrom by an annular bridging element 19 is a second ring 21. Said second ring 21 is provided with a plurality of air-control surfaces 23 that together define a frusto-conical member similar to the member defined by the surfaces of the first ring 11. Such surfaces 23 are constructed so as to provide spherical triangles similar to the spherical triangles of ring 11 but positioned intermediately of the triangles of ring 11, as shown in Fig. 3, the triangles of rings 11 and 21 having superposed apexes.

In the embodiment shown in Figs. 5 and 6 the ring 11 carries a control surface having an inner edge that forms an eighteen-sided polygon 25 circumscribing a rosette constructed of seven hexagons 27, so as to provide six equidistantly disposed inwardly pointing V-shaped projections. Diffusers such as the types shown in said U. S. Patent applications Nos. 655,358, 724,219 and 724,220 can be mounted in such hexagons. In addition, a star-shaped manifold 29 can be employed to facilitate fuel injection and control.

Figs. 7 and 8 show the air-control ring of Figs. 1 and 2 with the addition of curved-edge triangular inserts 31 between adjacent air-control surfaces. This provides a rose-window-like arrangement having a central rosette area of superior utility for use with multiple diffusers of the types shown in said U. S. Patent applications 655,358; 724,219 and 724,220, and can be used with or without conventional air registers of the types hereinabove mentioned. The ring 11 of Figs. 7 and 8 is shown to the opposite hand to that of the ring of Figs. 1 and 2 to indicate that either can be used for the purposes described.

It is to be noted that each additional intermediate control surface 31 likewise has the general shape of a spherical triangle, the apex of such triangle being located at the ring 11 and the two sides of such triangle being coincident with the two adjacent sides of adjacent control surfaces 13. The bases of the spherical triangles 31 and the apexes of the control surfaces 13 form semi-circles, each constituting a portion of the periphery of a seven-tangent-circle rosette 33, the whole resembling what is known in architecture as a rose or marigold window with tracery. Diffusers 35, such as the diffusers disclosed in said U. S. Patent applications 655,358; 724,219 and 724,220, are shown in phantom in the center and the petals of the rosette. A star-shaped fuel manifold 29 is also shown in phantom.

In operation, air entering laterally against the frusto-conical air-register doors of the furnace is directed along the doors and against the air-control surfaces hereinabove described, prohibiting direct flow into the furnace chamber and causing the air to be formed into the flow pattern of a closely wound helix. Even if no other register is employed, such a flow pattern tends to concentrate an air mass about the fuel-injector elements, thereby assuring more complete combustion and preventing dispersal of the flame pattern away from its desired position proximate the fuel-injector elements. Encompassing the peripheries of the circularly disposed multiple

air diffusers to an extent of the order of 50% or more, as indicated in Figs. 5 and 6, has a pronounced steadyng effect on air flow intermixture taking place in the plane of the fire face of such diffusers. By virtue of the design and position of the air foil surfaces 13 and 25, optimum operation of multiple-rosetted firing devices is obtained. In effect, component members of the cluster operate as satisfactorily and efficiently as though each one were disposed separately on a fire front and possessed a completely circular furnace opening ring of its own.

Obviously many modifications and variations of the present invention are possible in the light of the above teachings. It is therefore to be understood that within the scope of the appended claims the invention may be practiced otherwise than as specifically described.

The invention described herein may be manufactured and used by or for the Government of the United States of America for governmental purposes without the payment of any royalties thereon or therefor.

I claim:

1. A furnace air-control ring comprising an annular element adapted to be seated in the throat of a burner and a plurality of triangular deflecting plates having bases defining a line common with the inner circumference of said element and extending inwardly therefrom, said plates defining non-planar surfaces diverging shallowly from the plane of said element.

2. A furnace air-control ring comprising an annular element adapted to be seated in the throat of a burner and a plurality of triangular deflecting plates having bases defining a line common with the inner circumference of said element and extending inwardly therefrom, said plates defining non-planar surfaces having edges of equal radii and diverging shallowly from the plane of said element.

3. A furnace air-control ring comprising an annular element adapted to be seated in the throat of a burner and a plurality of spherical triangle deflecting plates extending inwardly therefrom, said plates defining non-planar surfaces diverging shallowly from the plane of said element and having bases defining a line common with the inner circumference of said element.

4. A furnace air-control ring comprising an annular element adapted to be seated in the throat of a burner and a plurality of spherical triangle deflecting plates extending inwardly at a shallow angle therefrom to define the central air opening of such burner.

RALPH C. BRIERLY.
